US00D994662S

(12) **United States Design Patent** (10) **Patent No.:** **US D994,662 S**
(45) **Date of Patent:** **** Aug. 8, 2023**

(54) **COMPUTER**

- (71) Applicant: **GETAC TECHNOLOGY CORPORATION**, Hsinchu County (TW)
- (72) Inventor: **Shuan-Yeong Ju**, Taipei (TW)
- (73) Assignee: **GETAC TECHNOLOGY CORPORATION**, Hsinchu County (TW)

(**) Term: **15 Years**

(21) Appl. No.: **29/786,044**

(22) Filed: **May 28, 2021**

(30) **Foreign Application Priority Data**

Apr. 1, 2021 (CN) 202130181373.4

(51) **LOC (14) Cl.** **14-02**

(52) **U.S. Cl.**

USPC **D14/314**; D14/441

(58) **Field of Classification Search**

USPC D10/46, 104.1, 106.1; D13/184;

D14/300, 301, 302, 308, 311, 312, 314, D14/348, 349, 350, 351, 352, 353, 354, D14/355, 439, 440, 441, 444, 445, 446, D14/496, 498, 502, 503, 504, 125, 135, D14/188, 189, 193, 194, 203.1, 203.2, D14/210, 299, 328, 329; D21/324, 332

CPC A63F 2009/2485; A47B 2200/0067; G06F 1/181; G06F 1/182; G06F 1/183; G06F 1/184; G06F 1/185; G06F 1/186; G06F 1/187; G06F 1/188; G06F 1/12; G06F 1/16; H05K 7/14; H05K 7/1422; H05K 7/1425; H05K 7/1427; H05K 7/1489; H05K 7/18; H05K 7/183; H05K 7/20; H05K 7/20181; H05K 7/20127; H05K 7/20145; G11B 33/125; G11B 33/127; G11B 33/14; G11B 33/1412; G11B 33/1446; G11B 33/146

CLAIM

The ornamental design for a computer, as shown and described.

DESCRIPTION

FIG. 1 is a top, front, and right side perspective view of a computer, showing my new design;

FIG. 2 is a bottom, rear, and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash lines in the figures illustrate the portions of the computer that form no part of the claimed design.

1 Claim, 8 Drawing Sheets
